UNITED STATES PATENT OFFICE

ALFRED J. FLAUDER, OF BRIDGEPORT, CONNECTICUT, ASSIGNOR TO THE WEIDLICH BROS. MFG. CO., OF BRIDGEPORT, CONNECTICUT, A CORPORATION OF CONNECTICUT

DESIGN FOR AN ATHLETIC TROPHY

Application filed March 19, 1931. Serial No. 39,156. Term of patent 7 years.

To all whom it may concern:

Be it known that I, ALFRED J. FLAUDER, a citizen of the United States, and a resident of Trumbull, in the county of Fairfield and State of Connecticut, have invented a new, original, and ornamental Design for an Athletic Trophy, of which the following is a specification, reference being had to the accompanying drawing, forming a part thereof, and in which the figure illustrates a front perspective view of an athletic trophy, showing my new design. The opposite side of the design is substantially the same as the side shown herein. I claim: The ornamental design for an athletic trophy substantially as shown and described. Signed at Bridgeport, in the county of Fairfield and State of Connecticut, this 14th day of April, A. D. 1931.

ALFRED J. FLAUDER.
